(57) CLAIM

The ornamental design for a non-marking interlocking strap device, as shown and described.

DESCRIPTION

FIG. 1 is a front view of the non-marking interlocking strap device embodying my new design,

FIG. 2 is a rear view thereof,

FIG. 3 is a left side view thereof,

FIG. 4 is a right side view thereof,

FIG. 5 is an enlarged top view thereof,

FIG. 6 is an enlarged bottom view thereof; and,

FIG. 7 is a perspective side view of the non-marking interlocking strap device of the present invention.
